HAIR DRIER

William Vere Rifle, Chicago, Ill.

Application August 22, 1932, Serial No. 629,779

2 Claims. (Cl. 34—18)

My invention relates to hair driers in which an increased dryness of the drying air is secured by heating it, and this heated air is forced through a duct and delivered and applied to the hair of one or more persons through a suitable air distributing hood or hoods.

The paramount object of my invention is to provide an efficient multiple hood hair drier capable of giving perfect service at low operating cost and low first cost; salient objects are, first, to provide an efficient means for utilizing the available heat in the fuel; second, to provide adequate means for preventing objectionable condensation in the combustion chamber and its connecting flue; third, to provide adequate means for maintaining the drying air at a reasonably uniform temperate temperature; fourth, to provide adequate means for regulating the temperature of the drying air at each individual service equipment; fifth, to provide a simple means of automatically controlling the supply of fuel in accordance with the heating service required; and sixth, to provide means for adjusting the elevations of hoods and nozzles to suit persons of different stature when sitting. These and other objects are attained by the means herein described and illustrated in the accompanying drawings, in which—

Figure 1 is a perspective view of a preferred embodiment of my apparatus in which a part of the casing and heating drum have been broken away to show the gas burner; Fig. 2 is a longitudinal vertical section along a part of the air distributing duct 16, showing the location and a cross section of the air baffle 51; Fig. 3 is an enlarged plan or top view of the air baffle 51; Fig. 4 is a side elevation of one air conduit equipped with an air nozzle and a hood, and arranged to take both heated and unheated air under pressure; Fig. 5 is a combination piping and wiring diagram showing the general arrangement of the gas control valves and electric switches; Fig. 6 is a vertical section passing through the center line of an air conduit equipped with a hood and having an inlet and pipe arranged to draw in unheated air at atmospheric pressure; Fig. 7 is an enlarged rear view or elevation of an air conduit having an inlet arranged to draw in air at atmospheric pressure; and Fig. 8 is a vertical section passing through the center line of an air conduit equipped with a hood and having an inlet arranged to draw in air at atmospheric pressure.

Similar numerals refer to similar parts throughout the several views.

Referring to Fig. 1, the plate 11, corner angles

12, shelf supports 13, shelf 14, an outer casing 15, air duct 16 and duct support 17 constitute the framework of the apparatus. The shelf 14 carries a motor driven low pressure blower 18 having an outlet 19 through the plate 11. The plate 11 carries a heating drum 20 having a plain top 20a and a pleated metal side 20b enclosing a combustion chamber. The bottom of the heating drum is partly enclosed by an inverted frustum of an oblique cone 23 having an opening 10 24 at its base to provide space for a burner 25 and a pilot lighter 26.

The heating drum is heated by burning either liquid fuel or gas, the supply of which is regulated by electrically operated controlling equipment. The frame work carries fuel controlling and safety equipment of which one arrangement adapted to the use of gas and alternating current is shown.

Referring to Fig. 5, the primary air valve 27 and 20 a flame adjustment valve 28 are located immediately adjacent the gas burner 25, and a magnetic gas valve 29 is located in the gas line between the flame adjustment valve 28 and the service valve or gas cock 30 on the general gas supply line 31. 25 This magnetic gas valve is designed for use in cooperation with a two wire mercury switch type thermostat, and is operated by direct current at twenty (20) volts. This magnetic gas valve closes automatically if a power failure occurs. 30

The tip 26a of the automatic pilot 26 is located so that flame from the pilot will ignite gas from the burner. This automatic pilot 26 is designed for use in cooperation with the magnetic gas valve 29. In case the pilot light goes out, the 35 thermostatic element 32 of the pilot contracts and causes the pilot switch 26b to open—breaking the low voltage thermostatic circuit 33 to the magnetic gas valve 29, and causing it to close and cut off the supply of gas to the burner 25. 40 The flame adjustment is regulated by the gas valve 34 located adjacent the pilot.

A two wire low voltage, mercury switch type thermostat 35 is located in the air duct 16 between the heating drum 20 and the first service 45 outlet 36. This thermostat is designed to operate within a temperature range of 80 to 140° F. and on an adjustable temperature differential of from two to five degrees. The thermostat is mounted at an opening in the wall of the air duct so that the temperature adjusting pointer 37 is conveniently located on the outside of the air duct and the temperature sensitive bimetal 38 will be in the stream of heated air when the apparatus is in operation.

When the thermostat 35 is set for operation at say 110° F. with a differential of two degrees, (the differential range being 109° F. to 111° F.) if the temperature in the duct 16 shall rise to 111° F. the 5 mercury switch 35a will open, thus opening the circuit to the magnetic valve 29 and causing it to close and cut off the supply of fuel. As soon as the temperature in the duct 16 shall have fallen to 109° F. the mercury switch 35a will automatically be closed by the thermostat 35, which condition restores power to the magnetic valve 29 and causes it to open and again permit the passage of fuel to the burner 25 provided of course that the pilot light is burning all of the time.

10 A power circuit 39 supplies alternating current at 110 volts through the line switch 40 for driving the motor 41 which is directly connected to the blower 18. The rectifier transformer 42 converts the 110 volts alternating current to twenty (20) 20 volts direct current which is used to operate the magnetic gas valve 29.

Referring again to Fig. 1, the plate 11 also carries a heat insulated casing 43 enclosing an air distributing and air mixing chamber extending 25 above the heating drum, and surrounding the heating drum and its frustum of a cone above the plate 11. To facilitate the distribution of the drying air before heating, a disk 45 perforated with large holes may be placed in the air distributing and air mixing chamber thus dividing it into two parts, the lower part 44a, and the upper part 44b. The distribution of the drying air before heating is greatly improved also by the use of a baffle or short elbow 46 placed at the outlet 19 so as to deflect air from the blower around the frustum of the cone. The air duct 16 for distributing heated air is connected to an outlet 47 of the upper part of the air distributing and mixing chamber 44b near its top. The pipe 48 30 is connected to the outlet 49 of the combustion chamber and serves not only as a flue for the combustion chamber but also as means for transferring heat from the flue gases to the drying air passing through the air duct 16.

40 The air duct 16 has a series of outlets 36, 50, each of which is connected to an air conduit leading to an individual service equipment. In order to provide approximately the same quantity of air at each of the outlets, as they may be used, 50 the outlets 36 nearer the heating drum are larger than the most remote outlet 50; in addition an air baffle 51 is located inside the air duct 16 as shown in Fig. 2. Each baffle has the form shown in Fig. 3 and may be bent along the line 52 so that the 55 quantity of air deflected by it may be varied as may be found necessary or desirable.

At the present time, the demand for hair drying equipment using heated air under pressure, requires two types of apparatus, one blowing air 60 through an air nozzle, and the other arranged for distributing heated air over the head through a hollow helmet or hood. Referring to Fig. 8, the hood 53 is attached to a curved air conduit 54a by the bolted hinge 55. When blown air is required, the hood 53 is moved to the position 53aa shown dotted, and as shown in Fig. 4 an air nozzle 56 is placed on the end of the curved air conduit 54 and held in place by a friction fit.

An important feature is the means employed 70 for adjusting the individual air service hoods to correct vertical positions for persons of different heights. Referring to Fig. 4 and also Fig. 1, a suitable wide cylindrical bearing plate 57 is fastened to the air duct 16. An opening 50 passes 75 through both the bearing plate and the air duct.

A narrower band 58 is fastened to the curved air conduit 54 in front of the air duct 16, and extending nearly around it, terminates in a projecting lip 58f at the back of the air duct 16. The curved air conduit 54 is also provided with a cylindrical bearing surface 54c and a projecting lip 54f. A sheet of vulcanized fibre 59 is placed between the contacting bearing surfaces of the plate 57 and the curved air conduit 54. The band lip 58f and conduit lip 54f are held nearly together by two 10 bolts 60 fitted with wing nuts 61. The wing nuts are set just tight enough so that the hood 53, when fastened to the curved air conduit 54a as shown in Fig. 8, can be easily moved up and down and set at any desired elevation—the air conduit 15 and its band being rotated slightly with respect to the air duct 16. Referring again to Fig. 4, the rotary movement of the air conduit 54 is limited to desirable amounts by providing a slot 63 in the band 58 for the pipe 72 conveying un- 20 heated air.

Referring to Fig. 8, the spring catch 64 and engaging pin 65 are provided opposite the hinge 55 to clasp the hood 53 rigidly to the curved air conduit 54a. This permits moving the hood to a 25 higher position by simply pushing it upward—the longer leverage secured by making the hood and curved air conduit rigid—saving both manual effort as well as providing greater convenience.

Referring again to Figs. 1 and 4, the quantity of 30 air passing to each individual service equipment is regulated by a butterfly valve 66 placed near the outer end of its curved air conduit 54. The valve 66 is provided with a lever arm 67 on each side of the air conduit 54, one to close it and the 35 other to open it. A pull cord 68 from each lever arm passes through an eyelet 69 fastened to the corresponding side of the hood. The maximum air capacity setting of the valve is provided by a stop pin 70 attached to the valve plate 66. 40

An important feature also shown in Fig. 4, is 45 means for regulating the temperature of air delivered to individual service equipment. Means for securing this desirable service are provided by inserting a pipe 72 through an opening 71 in the back of the air duct 16 at the curved air conduit 54. The pipe 72 is connected to an air pipe line 73 supplying unheated air from the blower 18 at low pressure. Further, the pipe 72 is provided with a valve 74 for regulating the quantity of 50 unheated air. One end of the pipe 72 projects from the inside of the duct 16 through its outlet 50 and into the curved air conduit 54. The curved air conduit 54 provides space for mixing the heated air from the air duct 16 with the un- 55 heated air from the air pipe 72.

Another important feature shown in Figs. 7 and 8 is means for regulating the temperature of air delivered to individual service equipments by diluting the heated air with air taken directly 60 from the atmosphere. Means of accomplishing this desirable service are provided by placing an air baffle or partition 75, inside the curved air conduit 54a and arranged to partially cover an opening 73a through the back of the curved air 65 conduit 54a. The opening 73a in the back of the curved air conduit 54a is provided with a sliding air valve 76 for regulating the quantity of air taken at atmospheric pressure.

An important modification of the means for 70 regulating the temperature of air delivered to individual service equipments is shown in Fig. 6. This modified means is provided by inserting a pipe 72b through an opening 73b in the curved air conduit 54b and placing a valve 74b in the 75

pipe 72b. One end of the pipe 72b projects inside the curved air conduit 54b sufficiently so that heated air flowing through the air conduit 54b will draw in air at atmospheric temperature and 5 pressure when the valve 74b is open or partly open. The temperature of the resulting mixed air will then be lower than the prior temperature of the heated air. Although the amount of temperature regulation which can be secured by this 10 means is limited, nevertheless it is sufficient to be satisfactory when the temperature of air supplied to the air duct 16 is not unusually high.

The casing 43 is covered with a heat insulating material 77. Other parts, except as otherwise 15 herein described, are of suitable metal.

While I have shown and described a certain form of my invention, selected for purpose of illustration, it is to be understood that it is capable of many modifications. Changes, therefore, 20 in the construction and in the arrangements may be made without departing from the spirit and scope of the invention as defined in the appended claims, in which it is my intention to claim all novelty inherent in my invention as broadly as 25 possible in view of the prior state of the art.

What I regard as new, claim, and desire to secure by Letters Patent is:

1. A hair drier comprising a heating drum provided with a conical bottom, an exhaust flue extending horizontally from said drum, a casing surrounding said drum in spaced relation with

respect to the side and top and bottom walls thereof and provided with a hot air duct surrounding said exhaust flue, a conduit depending from said conical bottom through the bottom wall of said casing, a source of heat in said conduit for supplying hot gases to the interior of said drum, a hot air applying member carried by said duct, and a blower beneath said casing provided with an outlet projecting through the bottom wall of said casing for directing air to be heated against 10 said conical bottom for distribution therefrom upwardly along and over said drum and to and through said duct for delivery to said applying member.

2. A hair drier comprising a casing having top, 15 bottom and side walls, a heating drum therein provided with similar walls spaced from the corresponding walls of the casing to provide an intervening heating chamber coextensive with the surface of the drum, a conduit extending from the 20 bottom wall of said drum through the corresponding wall of said casing, a source of heat for supplying hot gases to said drum through said conduit, a conduit extending into said casing beneath the bottom wall of said drum for supplying air 25 to be heated, a hot air supply duct communicating with said chamber and extending horizontally from said casing adjacent the upper end thereof, and a hot air applying member communicating with said duct and carried thereby. 30

W. VERE RIFLE.
